[57] CLAIM

The ornamental design for a security console, as shown and described.

DESCRIPTION

FIG. 1 is a front elevational view of a security console showing our new design;

FIG. 2 is a top view thereof;

FIG. 3 is a side view thereof; and

FIG. 4 is a perspective view thereof.

The perforations are partially shown in FIG. 1 for convenience of illustration, it being understood that the perforations are uniformly continuous over the area indicated.

The rear is flat and unornamented.

FIG. 2

FIG. 1

FIG. 3

FIG. 4
